NOZZLE CONSTRUCTION FOR SUCTION
CLEANERSGeorge A. Brace, Highland Park, Ill., assignor to
The Hoover Company, North Canton, Ohio, a
corporation of Ohio

Application June 10, 1948, Serial No. 32,117

8 Claims. (Cl. 15—416)

1

The present invention relates to the art of suction cleaners and more particularly to a surface contacting cleaning nozzle construction for use with suction cleaning apparatus.

It is a particular object of the present invention to provide a cleaning nozzle which is readily convertible by a simple movement on the part of the operator from a normal comparatively large area nozzle to a small area nozzle through which the air flows with a high velocity for the purpose of picking up threads and similar articles which cannot be picked up by the nozzle in its usual and normal condition.

More particularly it is an object of the present invention to provide a suction cleaning nozzle with an auxiliary nozzle mounted therewith selectively movable from an operative position in which it forms the sole air inlet to the suction cleaning apparatus to an inoperative position in which the same is completely inoperative to perform a cleaning function though still carried within the nozzle construction.

It is a further object of the present invention to provide a cleaning nozzle for a suction cleaner having mounted therewith a second, selectively usable, high velocity nozzle which opens a bleed air inlet port when moved to its operative position and seals such auxiliary air port to the nozzle when moved to its inoperative position.

Other and further objects of the invention will become apparent as the description proceeds when taken in connection with the accompanying drawings in which:

Figure 1 is a front elevational view partly in section of my nozzle construction shown connected to a suction cleaner unit;

Figure 2 is a sectional elevational view of the apparatus of Figure 1 taken substantially on the lines 2—2 thereof and looking in the direction of the arrows;

Figure 3 is a sectional elevational view of the apparatus of Figure 1 taken substantially along the line 3—3 and showing the auxiliary nozzle in operative position; and

Figure 4 is a view similar to Figure 3 showing the auxiliary nozzle in its inoperative position.

Referring now to the drawing in detail and first to Figure 1 thereof, there is illustrated a suction cleaning apparatus 1 of the so-called tank type which extends a suction hose 2 which is connected to a rigid or semi-rigid cleaning wand 3 which carries the surface contacting nozzle 4 upon its free end.

The nozzle 4 includes the usual swiveled outlet connection 5 which connects directly to the wand

2

3 to communicate the source of suction to the hollow interior of the nozzle. The nozzle is provided with a substantially rectangular elongated opening 6 in its bottom face which is bounded by a surface contacting marginal wall 7 defining the perimeter of the suction cleaning air inlet to the nozzle 4.

The interior of the nozzle is provided with a pair of downwardly projecting partition elements 8 intermediate the ends thereof on opposite sides of the point at which the swiveled outlet connection 5 connects to the nozzle 4 proper. The elements 8 terminate well above the floor contacting surface 7. Only one of the interior partitions 8 is shown in Figure 1 but an identical element is positioned in the right hand side of the nozzle 4 in Figure 1.

Each partition 8 supports a swivel pin 9 which pivotally supports a secondary high velocity nozzle construction 10. As shown most clearly in Figures 3 and 4 the nozzle construction 10 comprises wedge shaped end plates 11 which lie against the facing walls of the partitions 8. The plates 11 support a rigid plate 12 extending therebetween and provided with a projecting narrow air inlet nozzle portion 13.

The nozzle 13 is in the form of a long narrow rectangular slot which lies in a plane inclined to the surface to be cleaned when the nozzle is in operative position as shown in Figure 3. The front or leading edge of the nozzle 13 is thus substantially in contact with the surface undergoing cleaning and the rear edge of the nozzle is spaced above such surface to allow free flow of cleaning air into the nozzle.

The rear wall of the nozzle 4 between the partitions 8 is defined by a curved plate 15 secured at 16 to the nozzle 4. A foot portion 17 of the plate 15 completes the perimeter of the nozzle opening 6 and lies in the plane of the lower ends of the front and side portions of the wall 7. Air inlet ports 14 are provided in the curved plate 15 to admit air to the interior of the nozzle 4 above the plane of the surface contacting foot 17.

When the secondary nozzle 10 is in the position shown in Figure 3, the rear edge of the plate 12 engages the upper inner surface of the plate 15 to form an air seal which prevents air admitted through openings 14 from flowing into the region above plate 12 except through the nozzle opening 13. Similarly the front edge of the plate 13 engages in a sealing notch 18 formed in the front marginal wall 7 to prevent air flow into the region above plate 12 at this point. The end plates 11 of the nozzle structure 10 abut the partitions

8 and edge engage the front wall 1 of the nozzle structure to seal the ends of the plate 12. Thus when the nozzle 10 is in the position shown in Figure 3, air can enter the region above the plate 12 only by first passing through the high velocity nozzle 13.

Guide arms 20, see Figure 2, are secured to the outer sides of the plates 11 and terminate in cylindrical surface engaging feet 21. In the operative position of the nozzle 10 shown in Figure 3, the guide arms 20 extend toward the front of the nozzle structure 4 and lie in recesses 22 shaped to accommodate their lower ends with the nozzle 10 in operative position and the feet 21 engaging the surface to be cleaned. The upper ends of the arms 20 are bent at right angles to the planes of the plates 11 to provide ears 23 which are slotted to receive the free ends of light leaf springs 24. The leaf springs 24 are carried by brackets 25 secured to partitions 8. The leaf springs 24 bias the nozzle structure 10 to a neutral position in which the guide arms 20 depend vertically below the nozzle opening 6 as indicated in dotted lines at "a" in Figure 2.

As shown in Figure 2 the surface engaging foot 21 is in its extreme forward position with the bottom thereof lying in the plane of the bottom wall of the marginal structure 7. The foot 21 is moved to this position when the operator first places the nozzle upon the surface to be cleaned by giving it a slight rearward movement. After once being moved to this position the angle of the arm 20 is such that it will not ride backwardly to the dotted line position "a" as long as the nozzle is maintained in contact with the surface to be cleaned regardless of the direction in which the nozzle may be moved in the cleaning operation. Movement of the arm 20 to the full line position shown in Figure 2 rotates the secondary nozzle structure 10 to the position shown in Figures 2 and 3 in which position the cleaner is conditioned for operation with the high velocity nozzle 13.

If the operator desires to use the full nozzle for cleaning operation the cleaner is given a slight forward movement as it is first contacted with the surface to be cleaned. This rotates the arms 20 from vertical position to the rear dotted line position shown in Figure 2 in which position the arm 20 will remain as long as the nozzle is contacting the surface to be cleaned regardless of the direction in which it is moved. When moved to the rear dotted position shown in Figure 2, the secondary nozzle structure 10 is rotated to the position shown in Figure 4. In this position the nozzle opening 13 is inoperative and the front portion of the plate 15 including the openings 14 to seal the openings 14 and prevent further flow of air therethrough as shown in Figure 4.

The present invention is characterized by the provision of a suction cleaner floor contacting nozzle of conventional structure modified to incorporate within itself a selectively operable auxiliary nozzle structure having a comparatively small air inlet to provide for extremely high velocity air flow therethrough. The auxiliary nozzle is rendered operable or inoperative at the will of the operator simply by the manner in which the cleaning tool is first placed upon the surface to be cleaned. That is, a slight rearward movement of the nozzle structure as it is placed upon the surface to be cleaned shifts the auxiliary

nozzle into its operative position and simultaneously opens the bleed ports 14 which will allow a large quantity of air to enter the nozzle structure beneath the plate 12 to aid the cleaning action of the high velocity nozzle 13. A slight forward movement of the nozzle as it is placed upon the surface to be cleaned shifts the guide arms 20 to the position indicated in dotted lines at "b" in Figure 2 which rotates the secondary nozzle to its inoperative condition in which it seals the bleed ports 14 so that the cleaning tool operates as a conventional cleaning nozzle just as if the nozzle 10 and bleed ports 14 were not provided.

For most ordinary cleaning purposes the nozzle area defined by the marginal structure 7 is adequate for cleaning purposes, however a straight air cleaner does not suck the air through this nozzle with a velocity sufficient to pick up certain types of litter such as threads which offer small area to be engaged by the air stream and which tend to cling to the nap of carpet and similar floor coverings. The narrow nozzle 13 will remove such litter. When the narrow nozzle 13 is in use a large volume of air sweeps through the openings 14 laterally across the surface to be cleaned and flows through the nozzle 13 with a high velocity which is sufficient to detach and remove threads and similar litter.

While I have illustrated and described the invention in considerable detail, it is to be understood that various changes may be made in the arrangement, proportion and construction of parts without departing from the spirit of the invention or the scope of the appended claims.

I claim:

1. A cleaning tool for suction cleaning apparatus comprising a hollow body portion forming a suction air passage terminating in an air inlet opening forming a surface cleaning nozzle, means for connecting the interior of said body to a source of suction, an element shaped to extend across said air passage and engage portions of said body to form a seal therearound between said connecting means and said nozzle, an air inlet in said element forming a second cleaning nozzle of smaller cross-sectional area than said first nozzle and arranged in surface cleaning position when said element is positioned across said air passage, said small area nozzle having a low lip to contact a surface undergoing cleaning and a high lip to extend slightly above a surface undergoing cleaning, means to admit air into said hollow body between said element in its cleaning position and the surface being cleaned, means movably mounting said element on said body for movement from a first position in which said element does not obstruct air flow to said connecting means to a second position in which said second nozzle is in cleaning position, and means selectively movable by engagement with a surface to be cleaned for moving said element to a selected one of said two positions.

2. A cleaning tool for suction cleaning apparatus comprising a hollow body portion forming a suction air passage terminating in an air inlet opening forming a surface cleaning nozzle, means for connecting the interior of said body to a source of suction, an element shaped to extend across said air passage and engage portions of said body to form a seal therearound between said connecting means and said nozzle, an air inlet in said element forming a second cleaning nozzle of smaller cross-sectional area than said first nozzle

and arranged in surface cleaning position when said element is positioned across said air passage, an atmospheric air passage in said body arranged to supply air from a region above said first mentioned nozzle to the region below said element when said smaller nozzle is in surface cleaning position, means movably mounting said element on said body for movement from a first position in which said element does not obstruct air flow to said connecting means to a second position in which said second nozzle is in cleaning position, said element being arranged to block flow of air through said atmospheric air passage when in said first position, and means selectively movable by engagement with a surface to be cleaned for moving said element to a selected one of said two positions.

3. A surface cleaning suction tool comprising a body portion having an air passageway therethrough terminating in a first suction air inlet nozzle, a member mounted within said air passageway having a slot therein defining a second suction air inlet nozzle which is smaller than said first nozzle, said member being shaped to extend across said passage to block air flow therethrough except through said second nozzle, means movably mounting said member for movement between a first position in which it extends across said passage with said second nozzle in surface cleaning position to a second position in which it does not obstruct air flow through said passage and said second nozzle is removed from surface cleaning position, and means for moving said second nozzle member selectively to either of said positions comprising a surface contacting member mounted on said second nozzle member within said first nozzle for movement by engagement with a surface to be cleaned transversely to the length of said nozzle in the direction of normal cleaning movements thereof to either of two positions in which it shifts said second nozzle to one of its two positions, and means biasing said second nozzle member to a neutral position in which said surface contacting member extends through and depends below said first nozzle whereby the position of said second nozzle is determined by the initial direction of movement imparted to the tool when said element contacts a surface to be cleaned.

4. A surface cleaning tool comprising a body portion formed with an air passage therein terminating in a suction air inlet nozzle, an element shaped to extend across and engage the walls of said air passage, a second suction air inlet nozzle formed in said element and arranged in surface cleaning position when said element is positioned across said air passage, said second air inlet nozzle having a low lip to engage a surface undergoing cleaning and a high lip to clear a surface undergoing cleaning, an air inlet in said body above said first nozzle and opening into said air passage below said element when it is positioned across said passage, means movably mounting said element on said body portion for movement from a position across said air passage to another position in which it does not extend across said passage and said second nozzle is removed from surface cleaning position and said element having a portion thereof shaped to close said air inlet when it is in said another position.

5. A surface cleaning tool for suction cleaning apparatus comprising a hollow body having a portion forming a first surface cleaning air inlet nozzle, means for connecting the interior of said hollow body to a source of suction, an air inlet

port in said hollow body spaced above said first nozzle, a nozzle structure movably mounted on said hollow body having a second air inlet cleaning nozzle of smaller area than said first nozzle, 5 said nozzle structure shaped to engage portions of said hollow body above said first nozzle and said air inlet port to form an air seal around said nozzle structure with said second nozzle in surface cleaning position, said nozzle structure including means for closing said air inlet port when said nozzle structure is moved to a non-cleaning position, and means for selectively positioning said nozzle structure in a first position in which said air seal is formed or in said non-cleaning position.

6. A surface cleaning tool for suction cleaning apparatus comprising a body member having front and rear and end walls forming an air duct terminating in front and rear and end surface engaging lips defining a first suction air inlet nozzle, a pair of wall members in said air duct extending transversely of said front and rear walls adjacent to and spaced from said end walls and terminating above said nozzle lips whereby air 20 can flow from the region adjacent said end walls only under said wall members, a second suction air inlet nozzle formed in a barrier member shaped to engage said wall members and said front and rear walls between said wall members 25 to form an air seal therearound with said second nozzle in surface engaging position, means pivotally mounting said barrier member on said wall members for movement between a first position in which said second nozzle is in surface engaging 30 position and a second position in which said second nozzle is not in surface engaging position and said air seal is not established, a surface engaging actuating member secured to said barrier member for arcuate movement therewith between 35 a pair of stop positions in each of which said actuating member engages a surface being cleaned between said front and rear nozzle lips and rocks said barrier member to one of said positions thereof, and means biasing said barrier 40 member to a third position in which said actuating member lies between and depends below said front and rear nozzle lips.

7. A cleaning tool for a suction cleaning apparatus comprising a body member having walls 50 forming an air duct and surface engaging lips forming a first cleaning air inlet nozzle communicating with said air duct, means for connecting said air duct to a source of suction, a nozzle plate shaped to engage said walls to form an air seal therearound between said first nozzle and said connecting means, means on said nozzle plate forming a second air inlet cleaning nozzle having a lesser area than said first nozzle, means movably mounting said nozzle plate in said body 55 member for movement to a first position in which said second nozzle is removed from surface engaging position and said first nozzle has free communication with said air duct to a second position in which said nozzle plate engages said walls 60 in said air sealed relation and said second nozzle is in surface engaging position between and spaced from said first nozzle lips, means for selectively placing said nozzle plate in said first or said second position, an air port in said body member 65 in said air sealed relation and said second nozzle is in surface engaging position between and spaced from said first nozzle lips, means for selectively placing said nozzle plate in said first or said second position, an air port in said body member 70 positioned to admit air to said air duct above said surface engaging lips and below said nozzle plate in said second position, and means on said nozzle plate for closing said air port when said nozzle plate is in said first position.

8. A cleaning tool for suction cleaning appara-

7

tus comprising a hollow body portion forming a suction air passage terminating in an air inlet opening forming a surface cleaning nozzle, means for connecting the interior of said body to a source of suction, a pair of partitions in said hollow body portion spaced on opposite sides of said connecting means, each of said partitions extending downwardly from the top wall of said hollow body and terminating short of the lower end of said surface cleaning nozzle whereby air flow from the end portions of said hollow body to said connecting means must pass under said partitions, a nozzle plate in said hollow body having a suction air cleaning nozzle therein of smaller cross-sectional area than said first mentioned nozzle, said nozzle plate being shaped to engage said partitions and the portions of said hollow body between said partitions to form an air seal around said nozzle plate, means movably mounting said nozzle plate on said partitions for movement from a first position in which said plate engages said partitions and said portions of said hollow body and said small nozzle is in surface cleaning position to a second position in which said nozzle plate does not obstruct air flow from 25 said first mentioned nozzle to said connecting means and said small nozzle is moved to an in-

10
